UNITED STATES PATENT OFFICE.

STANLEY S. JOHNS, OF BALTIMORE, MARYLAND.

REPEATING ATTACHMENT FOR DISK-RECORD PHONOGRAHS.

Application filed March 15, 1922. Serial No. 544,001.

To all whom it may concern:

Be it known that I, STANLEY S. JOHNS, a citizen of the United States, residing at Baltimore city, in the State of Maryland, have 5 invented certain new and useful Improvements in Repeating Attachments for Disk-Record Phonographs; and I do hereby declare the following to be a full, clear, and exact description of the invention, such as 10 will enable others skilled in the art to which it appertains to make and use the same.

My invention relates to improvements in repeating attachments for disk records on disk phonographs, such as the well known 15 Victrola or other phonographs of similar character.

In the use of such instruments it is often desirable to provide an automatic repetition arrangement whereby the instrument may 20 be caused to play continuously, or as long as the turn-table continues to revolve, without the necessity of moving the needle back by hand with the consequent interruption in the music. Such devices are especially useful where these instruments are used to provide music for dancing.

With such arrangements it is essential not only to provide quick and positive means for returning the needle to the initial or 30 starting position; but it is also essential to protect the surface of the disk against being scarred by the needle as the tone arm is automatically swung back to the initial position.

It may be also desirable to adjust the 35 limit of swing of the tone arm so that parts only of the record may be played if desired. It is also desirable to provide a positive lock for holding the stop bar in the engaged 40 position, or out of the way in the disengaged position. It is also desirable to have no part of device touching record while playing. It is also an advantage to have a quick means of detaching device if desirable.

These and other features as will be hereinafter described are contained in the apparatus comprising my invention, which 45 will be more clearly understood after reference to the accompanying drawings in which like parts are indicated by similar 50 reference symbols throughout the several views.

Figure 1 shows a plan view of the parts in the assembled relation, with the needle

and the tone arm in the playing position, 55 and the stop bar extending over the disk in the operative position.

Figure 2 is an enlarged side elevation of the reproducer and the parts carried thereby, including the needle and its attachments, 60 as seen from the left of Fig. 1, the needle being in the playing position with regard to the disk.

Figure 3 is a similar view to Fig. 2, but shows the needle out of engagement with 65 the disk, and the resetting cam in the position for restoring the tone arm to the initial position.

Figure 4 is a plan view, partly in section along the broken line 4—4, of the apparatus 70 shown in Fig. 2.

Figure 5 shows a vertical section along the line 5—5 of Fig. 2, and looking in the direction of the arrows; parts being shown in elevation. 75

Figure 6 shows a section along the line 6—6 of Fig. 2, the re-setting cam and diagonal roller being shown in plan, and the parts being shown on a larger scale than in Fig. 2. 80

Figure 7 shows a section along the line 7—7 of Fig. 3, and looking down, the parts being shown on a larger scale than in Fig. 3, and the re-setting cam being shown in plan.

Figure 8 is a detail view, on a larger scale, 85 of the pivot end of the stop bar.

Figure 9 shows a section along the broken line 9—9 of Fig. 8, and looking in the direction of the arrows.

Figure 10 shows a modified form of attachment for use with the operating cam, the same showing a section along the line 10—10 of Fig. 11. 90

Figure 11 represents the device shown in Fig. 10 as seen from the left of said figure. 95

Figure 12 is a detail perspective view of the clamping ring shown in Figs. 10 and 11; and

Figure 13 is an enlarged sectional elevation of the friction bearing for the tripping lever. 100

A represents the cabinet which may be of any suitable form and construction, and provided with the flat top A', above which top is mounted the turn-table B provided with 105 the pin b, on which turn-table the record disk C is mounted in the usual way.

D represents the tone arm which is piv-

oted to the cabinet in the usual way, as at *d*, and carries the usual gooseneck *D'*, with the reproducer *E*, to which the needle *F* is connected in the usual way. As will be hereinafter described the automatic attachment may be readily adjusted to operate, irrespective of the length of the needle. Needles vary more or less in length, and in an attachment of this kind it is necessary to consider this fact.

The parts hereinbefore described are all well known in the art, and not being a part of my present invention will not be further described herein.

15 My invention more particularly relates to the means for lifting the needle from the record and for automatically restoring the reproducer and needle to the initial position, and also for limiting the swing of the tone arm; and the details of this invention will now be described.

Attached to the back of the reproducer *E* is the usual block *G*, preferably of rubber or non-resonant material, and this block is attached to the reproducer in any convenient way, as by the screw *g*.

The screw *H*, shown in detail in Fig. 4, passes through the plate *I* fast to the block *G*, which plate is provided with the stop arm *I'*, see Figs. 2, 3 and 5. The screw *H* is preferably provided with an annular flange *h*, with a reduced portion *h'*, on which reduced portion the arm *K* is pivoted. The said arm is held in engagement with the stop arm *I'* by means of the weak spring *L*. The purpose of this spring is to permit the flexibility of the parts and to hold the arm *K* in engagement with the stop arm *I'*, when height of cam is not being adjusted. This 40 arm *K* is provided with a socket *k* through which passes the standard *M* to which the resetting cam *N* is journaled, as will be hereinafter described.

The standard *M* may be adjusted at the 45 desired position in the socket *k* by means of the clamp screw *k'*, see Figs. 2, 3 and 4, and thus the height of the cam relative to the length of stylus may be adjusted. The standard *M* is made angular in shape, preferably rectangular, so as not to turn in its socket, and extending laterally from this standard is a horizontal arm *n'* (see Fig. 6) which serves as an axle on which the cam *N* is free to rotate. The outer surface of this 55 cam is covered with a layer of rubber, leather, or similar material *n*, and one side of the cam is flattened, as at *n'*, so as to be clear of the disk when the needle is in the playing position. This yielding material 60 serves as the actuating face of the cam.

Set diagonally across the face of this cam, and removed from the flattened portion *n'*, is the diagonal roller *P*, mounted on the diagonal shaft *p* connecting the two 65 side plates *n* of the cam *N*, as shown most

clearly in Fig. 6. The rotary cam is preferably weighted on the side opposite the flattened face *n'*, so that there will be a tendency of the cam to fall down by gravity from the disengaged position shown in Figs. 70 2 and 5 to the engaging position shown in Fig. 3. The cam is normally held in the position of unstable equilibrium, shown in Fig. 2, by means of the lug *n* engaging the arm *q* of the tripping lever *Q*, which is held by frictional engagement in any desired position by means of a screw *Q'* having a cup-shaped head *q'* enclosing the spring *q*, see Figs. 2, 3 and 13.

This lever *Q* may be provided with an 80 upwardly projecting flange *q* which serves to stiffen same, and also to limit the side motion of said lever, as shown in Figs. 6 and 7. The lever *Q* is also provided with a tripping arm *q* adapted to strike one or the 85 other stops on the stop bar *R*, which carries the two adjustable stop arms *S* and *S'*, each of which may be clamped in place on the bar *R* by means of the clamp screws *s* and *s'*, respectively. These arms *S* and *S'* project 90 down into the path of the tripping arm *q* in the operation of the instrument, and may be provided with bearings of rubber or other suitable material to prevent clicking.

The bar *R* is preferably curved when in 95 the engaging position, as shown in Fig. 1, with the same center as the tone arm. The bar is held in either the engaging position shown in Fig. 1, or in the disengaged position clear of the disk by a special locking 100 arrangement which is shown in detail in Figs. 8 and 9, in which *T* represents a tubular casing projecting up from the top *A'* of the cabinet, in which casing is enclosed a pivot pin *U* surrounded by a coil spring 105 *V*. This pin *U* is fast to the socket *R'*, secured to the end of the bar *R*, and the spring *V* normally tends to press said pin down, as shown in Fig. 9, causing one or the other of the notches *r* and *r'*, see Fig. 8, to engage 110 the pin *t* projecting outwardly from the casing *T*.

When the notch *r'* engages the pin *t*, the bar *R* will be locked over the disk in the position shown in Fig. 1, but when the bar 115 *R* is swung outwards until the notch *r* engages the pin *t*, the said bar will be entirely clear of the disk and the disk may be removed and new disks applied without being inconvenienced by the position of said bar. 120

By this spring lock arrangement just referred to, the bar may be swung into the engaging position, or out into the disengaged position, and automatically locked in either position.

In the modification shown in Figs. 10 to 12, instead of connecting the attachment to the block *G*, as shown in Figs. 1 to 5, I connect it to the gooseneck *D'* by means of a split collar *X* held fast on the tube *D'* by 130

means of the clamp screw α passing through the ears α' . This collar has a perforated lug α^2 (see Figs. 10 and 12) to hold the stop pin i , similar in function to the pin i shown 5 in Figs. 2 and 3.

This collar also has a lug α^3 holding the horizontal pin Y which serves as a pivot for the arm K , in which the standard M is adjustably held.

- 10 The cam N and other parts carried by the standard are similar to those already described with reference to Figs. 1 to 9. The mode of connecting the attachment by means of a collar clamped in the gooseneck 15 facilitates the addition of the attachment to various types of talking machines.

The operation of the device is as follows:—

Place the needle or stylus in holder provided in the usual way. Turn cam in 20 position of Fig. 2, tripping arm q^3 to left. Place stylus on record and unscrew knurled screw K' which clamps standard M in arm K . This will allow both cam and stylus to 25 touch record; with fingers on screw K' , press down arm K compressing spring L until motion is stopped by head of screw i coming in contact with plate I' ; tighten screw K' and release spring L , which will now lift 30 arm K carrying standard M to position shown in Fig. 2, allowing sufficient clearance between cam N and record to avoid rubbing.

The cam being in the inoperative position shown in Figs. 1, 2 and 6, and being held in this position by the engagement of the lug n^o , with the arm q of the lever Q , and the stop bar R , being thrown to the position shown in Fig. 1, and the stop arms 35 S and S' being adjusted to the proper position by means of the corresponding clamp screws, start the instrument to playing. As the tone arm swings towards the pivot of the disk, the tripping lever Q will ultimately strike the inner stop arm S , releasing the arm q of the lever Q from engagement with the lug n^o of the cam N , and the cam being in unstable equilibrium will swing from the position shown in Fig. 2 40 towards the position shown in Fig. 3, so that the soft engaging face of the cam will engage the top of the disk and the diagonal roller P will bear on the upper surface of the disk.

The partial revolution of the cam to the engaging position will cause the lug n^o to engage the arm q^3 of the lever Q as shown 45 in Fig. 7, and thus the cam can rotate no further until this lever is released; the parts 50 then being in the position shown in Fig. 7. When in this position the diagonal roller P will quickly swing the tone arm back towards the initial position until the arm q^3 of the lever Q strikes the stop arm S' , and 55 the cam will be released and the continued

movement of the disk will speedily restore the cam to the initial position shown in Figure 2.

Incident to this operation, the lowering of the cam will lift the reproducer so as to 70 clear the needle from the disk, and when the cam is thrown out of engagement the needle will be gently restored to engagement with the disk by the eccentric motion of cam in revolving in contact with disk. It will be 75 noted that during the backward movement of the tone arm the needle will be kept entirely clear of the disk, and will only engage the disk when the cam is in the inoperative position. By adjusting the position of the stop arms S and S' the angular swing 80 of the tone arm may be varied within limits, and records of different width, or desired parts thereof, may be played over and over again at will.

It will be obvious that the swing of the tone arm in one direction will be automatically caused by the engagement of the needle with the record, and in the other direction by the engagement of the diagonal 85 roller with the surface of the disk.

It will also be obvious that this reciprocating swinging movement of the tone arm will continue indefinitely as long as the turn-table is continued in rotation.

When it is desired to cease the repetition action referred to, throw out the stop bar to the disengaging position and it will be held locked in that position until ready for use. While in this position the instrument 100 may be used in the ordinary way and the disk records may be applied or removed without there being any inconvenience whatever occasioned by the repetition attachment thereinbefore described.

The standard M may be moved up or down in its socket and clamped at the desired position to compensate for changes in the length of the needle. Where the length of the needle varies it will be ordinarily 105 necessary to adjust the attachment according to the length of the needle used.

It will be obvious that the relative proportions of the cam and of the diagonal roller may be varied, and various other details of the apparatus might be changed in many respects; and I do not mean to limit the invention to such details except as particularly pointed out in the claims.

I claim as my invention:—

1. In a repeating mechanism for talking machines a return roller attachment carried by the sound producing means, comprising an eccentric roller provided on its periphery with a diagonally disposed rotatable element adapted to engage the face of a record.

2. In a disk record phonograph provided with a rotary turn-table, adapted to support a record disk, a laterally swinging tone arm, a reproducer swiveled to free end of 130

said tone arm, and a stylus carried by said reproducer, the combination with a revolvable cam carried by said reproducer, a diagonally disposed roller journaled at an angle to and having the outer engaging surface projecting beyond the edge of said cam, and means for tripping said cam and causing it to engage the disk.

3. A stop arrangement for use in apparatus of the character described, comprising a fixed tubular socket, a pin projecting from said socket, a tubular cap revolvably mounted thereon provided with holding notches therein, adapted to engage said pin, a screw bolt secured to said cap and projecting axially into said socket, so as to permit a rotary movement of said cap relative to said socket, and also a short

axial movement of said cap relative to said socket, a coil spring mounted on said screw bolt and normally pressing said cap down on said socket, a curved arm projecting laterally from said cap, and a stop arm mounted on said curved arm.

4. In a disk record phonograph having a reproducer and a stylus therefor, in combination, a standard connected to said reproducer, a cam pivoted to said standard, a roller journaled at an angle to and projecting beyond the edge of said cam, and automatic means for causing said cam and said roller to successively engage the surface of the rotating disk and first lift said stylus then return said reproducer, and finally restore said parts to initial position.

STANLEY S. JOHNS.
